UNITED STATES PATENT OFFICE.

HARRY T. DALE, OF NEW YORK, N. Y.

AMPLIFIER FOR TELEPHONIC TRANSMITTERS.

1,378,940.

Specification of Letters Patent. Patented May 24, 1921.

Application filed March 31, 1919. Serial No. 286,274.

To all whom it may concern:

Be it known that I, HARRY T. DALE, a citizen of the United States, and a resident of New York city, borough of Manhattan, in the county and State of New York, have invented certain new and useful Improvements in Amplifiers for Telephonic Transmitters, of which the following is a full, clear, and exact description.

10 Among the principal objects which the present invention has in view are: to perfect the transmission of audible sound waves to the diaphragm of an electric transmitter; to intensify the said sound waves; to avoid out-
15 side disturbances; to collect sound waves over a large area and concentrate the same upon the center of the recording disk; and to provide an attachment for the usual transmitter used in the mechanical aids for the
20 deaf, whereby the sound intensity may be augmented.

Drawings.

Figure 1 is an end view of an amplifier of
25 the character mentioned.

Fig. 2 is a side view of the same.

Fig. 3 is a section of the amplifier shown in conjunction with a transmitter of known construction, the section being taken as on
30 the line 3—3 in Fig. 1.

Description.

The amplifier is intended primarily for use in conjunction with the transmitters of
35 instruments used as aids for the deaf, and generally known in the trade by the name of audiphones.

As shown in Fig. 3 of the drawings, the transmitter indicated by the numeral 12 has
40 a cover cap 13. This cap usually presses upon a gasket which holds the diaphragm of the transmitter in service. A shoulder 14 is formed on the cover 13. This shoulder is taken advantage of when using the present
45 amplifier, the wall 8 of the amplifier being rabbeted to form a seat 15 which rests upon the shoulder 14. A relatively thin gripping section 9 is thus formed. The section 9 is employed to frictionally grip the side or
50 perimeter of the transmitter 12.

The amplifier is preferably constructed of hard rubber which is sufficiently resilient where the thin portion is formed to accommodate different characters of transmitters
55 and variations in the standard types.

The wall 8 of the amplifier is made thick

to avoid inherent vibration. At the upper edge of the wall 8, the material is shaped to form the inturned funnel-like member 10. It will be noted that the edge of the member 10 is made very thin toward the center and particularly adjacent the opening 11. The opening 11 registers with the perforated central portion of the cover 13. The wall terminating in the member 10 operates to concentrate the sound waves for delivery through the opening 11. The member 10 is depressed as best shown in Fig. 3 of the drawings to form an annular chamber 16.

Due to the depression of the thin wall of the member 10 at the opening 11, the air which is contained in the chamber 16 is substantially trapped. When the sound waves are delivered into the chamber or into the space between the outer wall of the amplifier 8 and the outer wall of the cover 13, the body of air in the chamber 16 is vibrated. Due to the shape of the inner surface of the said chamber, these vibrations are first deflected from the inner surface of the wall 8 to the over-hanging inner surface of the wall 10 to be thereby deflected toward the central perforated portion of the cover 13. The vibration of the air contained in the chamber 16 multiplies the effect on the diaphragm when delivered through the area covered by the perforations in the cover 13, directly over the center of said diaphragm.

As a result of this amplification of the vibration the sound waves are intensified and the diaphragm is more violently operated upon with the result that the microphone or transmitter 12 delivers a corresponding electric oscillation to the telephonic system including the receiver which is held at the ear 95 of the person using the audiphone.

It will be understood that if desired the amplifier may be removed from the transmitter 12, in which case, the said transmitter will perform its usual function in the usual 100 manner. When, however, the transmitter fails to give sufficient volume or intensity of tone, the amplifier 8 may be slipped into working position, the gripping section 9, tightly holding the amplifier in place.

While I prefer to manufacture the amplifier from hard rubber, it will be understood that a variety of materials may be used.

To assist the gripping portion 9 in accommodating a variety of sizes of the transmitter 12, I sometimes provide the edge 9 with longitudinal slits 17, as best seen in Fig. 2 of

the drawings. This separation of the thin portion 9, permits slight expansion thereof.

Claim.

- 5 As an article of manufacture, a removable slip cover for a telephonic transmitter, said cover having a relatively thick annular wall and a top, the center whereof is pierced to form a single contracted opening, said top

having an annular rigid portion adjacent 10 and integral with said annular wall; and a thin vibrant portion integrally formed with said annular portion adjacent the said opening for forming a sensitive vibrant member for amplifying the acoustic vibration under 15 said top.

HARRY T. DALE.
